SPIRIT LEVEL HOLDER

Filed Feb. 20, 1946

UNITED STATES PATENT OFFICE

2,557,291

SPIRIT LEVEL HOLDER

Richard T. Hubbard, Spokane, Wash.

Application February 26, 1946, Serial No. 648,876

1 Claim. (Cl. 33—211)

1

The present invention is directed to improvements in spirit levels.

The primary object of the invention is to provide novel means for adjusting the fluid containing leveling tubes, the construction being such that after adjustments are made the tubes will remain in their adjusted positions for indefinite periods.

Another object of the invention is to provide a device of this character so constructed that the tubes will remain in their adjusted positions should the level be subjected to undue shocks.

With these and other objects in view, this invention resides in the novel features of construction, formation, combination and arrangement of parts to be hereinafter more fully described, claimed and illustrated in the accompanying drawing, in which:

Figure 1 is a perspective view of a level.

Figure 2 is a side view, partly broken away.

Figure 3 is a perspective view of one of the holders for the horizontal leveling tubes.

Figure 4 is a similar view of a holder for one of the vertical leveling tubes.

Referring to the drawing, 1 designates the level body formed from wood or other suitable material, and formed with openings 2 adjacent its ends and a central opening 3.

Formed in one side of the body 1 and adjacent the opening 3 is a recess 4, while adjacent opposite ends of the openings 2 are formed recesses 5, the purpose of which will later appear.

Since the holder 6 for adjusting the tubes 7 for leveling horizontal surfaces are identical, the description of one will suffice for both.

These holders, as clearly shown in Figure 3 consist of suitable gauge sheet metal, and include an elongated strip 8, one end of which terminates in an inclined plate 9 and a terminal lip 10.

Each holder 6 further consists of a tube supporting cradle 11, the side edges of which are bent into engagement with the side edges of the strip 8, the ends of which terminate in angularly disposed heads 12, each having seats 13 formed therein for receiving and holding the ends of the tubes 7 firmly in place.

The holders are retained in the opening 3 upon embedding the ends of the strips 8, and the lips 10 in the body 1 and in the end walls of said opening, as shown in Figure 2 of the drawing.

Adjusting screws 14 are threaded in the body 1 with their heads positioned in the recesses 4 in order that they may be manipulated by a tool to adjust the holders, and thus the tubes 7.

The inner ends of the screws 14 engage the 55 adjacent heads 12 and obviously upon adjustment

2

of the screws the holders will flex, due to their inherent resiliency, thereby accurately calibrating the level.

The holders 15 for the vertical tubes 15 each consist of a sheet metal arcuate shaped strip 16, one end having tongs 17 and an off-set lip 18. When these holders occupy the openings 2 the tongs 17 and lip 18 will be embedded in the walls of the openings, thus retaining the holders in place.

The strips 16 have seats 19 formed in their ends and in which are engaged the ends of the respective tubes 15, there being recesses 20 formed in the walls of the openings 2 to receive the ends of the tubes 15 to permit movement thereof during adjustment.

Screws 21 are engaged in the body 1 and the heads thereof occupy the recesses 5, while their inner ends engage the strips 16 so that upon adjustment of the screws the holders 15 may be flexed for that part of their length not anchored by the tongs 17 and lips 18.

Since the respective holders are formed from sheet metal adjustment of the tubes can be easily and quickly made, and due to their inherent resiliency the tubes cannot be moved from adjustments due to shocks.

What is claimed is:

A holder for a bubble tube of a level comprising a mounting strip flat throughout the major portion of its length and having end portions adapted to be embedded in end walls of an opening formed in the body of a level and firmly hold the mounting strip in the opening longitudinally thereof, a saddle formed from a strip of resilient material extending longitudinally of said mounting strip and held in flat contacting engagement therewith by side extensions bent inwardly and having overlapping engagement with opposite side edge portions of the mounting strip, end portions of the strip forming said saddle being bent diagonally away from the mounting strip and then away from the diagonal portion and again bent inwardly to form hook shaped portions having bills adapted to overlie end portions of a bubble tube, the said bills being bent to form tube-engaging, free end portions extending inwardly at an incline and having corner portions bent to form prongs for engaging side portions of the tube and hold the tube-engaging end portions in pressing engagement with the tubes whereby the tube is firmly held against the diagonally extending portions.

RICHARD T. HUBBARD.
